UNITED STATES PATENT OFFICE.

ROBERT E. SHARP, OF ESBON, KANSAS.

NONSKID MUD AND SNOW DEVICE.

1,418,839.

Specification of Letters Patent. Patented June 6, 1922.

Application filed February 15, 1921. Serial No. 445,138.

To all whom it may concern:

Be it known that I, ROBERT E. SHARP, a citizen of the United States, residing at Esbon, in the county of Jewell and State of Kansas, have invented certain new and useful Improvements in Nonskid Mud and Snow Devices, of which the following is a specification, reference being had therein to the accompanying drawings.

10 This invention relates to non-skid mud and snow devices, and has for its object the construction of a device that can easily be fastened over the tire of a motor vehicle, and which will prevent skidding or creeping 15 upon an icy, or slippery, or muddy pavement or road.

With this and other objects in view, my invention comprises certain novel combinations, constructions and arrangements of 20 parts as will be hereinafter described, illustrated in the accompanying drawings, and more particularly pointed out in the appended claim.

In the drawings:

25 Figure 1 is a view, in side elevation, of a device constructed in accordance with the present invention, shown upon a rubber tire, while

Figure 2 is a top plan view of the same.

30 Figure 3 is a section, taken on line 3—3, Fig. 1, and looking in the direction of the arrows.

Figure 4 is a perspective view of the auxiliary link of the central fastening device, 35 while

Figure 5 is a perspective view of the primary link of the same.

Figure 6 is a perspective view of the casting of the side fastening devices, while

40 Figure 7 shows a blank of the same, prior to folding.

Figure 8 is an enlarged section, taken on line 8—8, Fig. 2, and looking in the direction of the arrows.

45 Figure 9 is an enlarged section, taken on line 9—9, Fig. 2, and looking in the direction of the arrows.

Referring to the drawings by numerals, 1 designates the rubber tire upon which is 5 placed my anti-skid and slipping device, which comprises transverse chains 2, a central chain 3 and side chains 4.

The transverse chains 2 comprise flat links 5 connected by round links 6.

55 The central chain 3 includes the central,

round links 6, Fig. 2, and the flat, central links 7.

The side chains 4 include flat, side links 8 and oblong links 9; each link 8 comprises a narrow solid body with looped ends, in which 60 ends the slideable links 9 are mounted. The length of the side chains 4 can be varied by turning the oblong links 9 to different positions in the looped ends of the links 8; for instance, at A, Fig. 1, the oblong link is 65 turned so that the side links 8 engage the corners of the link 9, giving a greater length to the side chain than if the side links 8 were engaging the long sides of the link, as the link is slightly oblong. When the links 70 8 are engaging the ends of the oblong links 9, as shown in Fig. 1, with the exception of the link at A, the chains are of the greatest length.

The ends of the central chain are connected by a central fastening device 10, Figs. 1, 2, 4 and 5. This central fastening device comprises a primary link 11 and an auxiliary link 12 (Figs. 4 and 5). The primary link 75 comprises a flat body 13, which has, at its inner end, a shoulder 14, and integral with the inner end is an open hook 15. The body 13 is provided with a plurality of vertical apertures 16. The auxiliary link 12 includes a flat body 17 in which are a plurality of parallel receiving and protecting grooves 18, and in the body 17, registering with the grooves 18, are apertures 19, which apertures 80 are adapted to register with apertures 16, of the primary link 11. Integral with one 85 end of the auxiliary link 12 is an open hook 20. The hooks 15 and 20, of the links of the central fastening device, receive round links 6 at the center or middle of the transverse chains, and these central, round links also 90 constitute a part of the central chain 3. A bolt 21 is placed in the registering apertures 16 and 18 of the primary and auxiliary links 11 and 12, respectively, and a pin 22 is placed 95 in the projecting upper end of the bolt 21, 100 the pin and upper end of the bolt being in one of the transverse receiving and protecting grooves 18 of the auxiliary link, Figs. 1, 2 and 8. This peculiar structure, shown particularly in Figs. 4, 5 and 8, produces an 105 admirable, central, fastening device which is very strong and durable in actual operation.

The ends of the two side chains 4 are connected by a pair of similarly-constructed side fastening devices, and it will only be 110

necessary to specifically describe one of the side fastening devices; said side fastening device comprises a sheet-metal casing 23, U-shaped in cross section, and this casing 5 comprises a body 24 having a neck portion 25, and in the neck portion is a link-receiving notch 26. The neck portion 25 is provided with ears 27, and in these ears are apertures 28. A pin 29 (Fig. 9) extends 10 through the apertures 28 and through a hooked end 30 of the end side link 8. The U-shaped body 24 straddles the central portion of the link 8, Figs. 2 and 6, and through the registering apertures 31, a pin 32 is 15 passed to prevent the body from moving off link 8. Upon removing pin 32, the casing can be swung out away from the central portion of link 8 upon its pivot, constituted by pin 29, and then upon removal of 20 pin 29, the oblong link 9 can be removed from the hook end 30 for disconnecting the ends of the side chains.

It is to be noted that I have produced a peculiar, central, fastening device, which is 25 not efficiently adapted for fastening the side chains, for I have provided peculiarly-constructed, side, fastening devices for fastening the ends of the side chains together.

While I have described the preferred embodiment of my invention, and have illustrated the same in the accompanying draw-

ings, certain minor changes or alterations may appear to one skilled in the art to which this invention relates, during the extensive manufacture of the same and I, therefore, 35 reserve the right to make such alterations or changes as shall fairly fall within the scope of the appended claim.

What I claim is:

In a device of the character described, the 40 combination of chains, a fastening device connecting said chains, said fastening device consisting of a primary link and an auxiliary link, each link including an elongated thickened solid body, said auxiliary link being slidably mounted upon said primary link, said primary link having an aperture 45 in its body, said auxiliary link having transversely extending grooves formed in the outer face of its body, said auxiliary link 50 having apertures formed in its body and communicating with said grooves, a bolt fitting within the aperture of said primary link and within a selected aperture of said auxiliary link and extending into the groove 55 communicating with the selected aperture of the auxiliary link, and retaining means engaging said bolt and fitting entirely within the groove, as and for the purposes set forth.

In testimony whereof I hereunto affix my 60 signature.

ROBERT E. SHARP.
